UNITED STATES PATENT OFFICE.

LAVINIA S. HODGSON, OF EMPORIA, KANSAS.

DESIGN FOR AN ANKLE ATTACHMENT FOR OVERSHOES.

SPECIFICATION forming part of Design No. 30,863, dated May 23, 1898.

Application filed February 19, 1897. Serial No. 624,261. Term of patent 7 years.

To all whom it may concern:

Be it known that I, LAVINIA S. HODGSON, a citizen of the United States of America, residing at Emporia, in the county of Lyons, in the State of Kansas, have invented and produced a new and original Design for Ankle Attachments for Overshoes, of which the following is a specification, reference being had to the accompanying drawings, forming a part thereof.

Figure 1 is a plan view of the blank, extended, from which the design is produced. Fig. 2 is a perspective of the design as it appears preparatory to attachment for use to the upper of an overshoe.

A designates my design for the ankle attachment, produced from a single piece of material, such as leather, and composed of rear ankle-pieces $a a^x$, having a contour, as shown, so that when the rear lines or edges are secured together the united pieces will partially surround the rear portion of the ankle above their connection to the shoe, as indicated in Fig. 2 of the drawings, and from the front lower portions of these rear ankle-pieces are produced narrow extensions $b b^x$, the lower lines of the extensions being carried into and curved upward, as at c , to produce the baseline of the front ankle-flap d . The front ankle-flap d has its opposite lower edge lines car-

ried inward, as at e , and then outward, producing curved and rounded side extensions $f f^x$, and upward-extending portion g , produced by having its edge lines carried upward from both extremities in undulating curves 35 rising to the middle or center, as shown in the drawings.

In use the ankle attachment is suitably connected at its lower edges to the upper edge of the opening in a shoe by a line of stitches, 40 and the front ankle-flap d lies with its produced lateral extremities reaching over and outside of the front portions of the heel-pieces and the upper portion lying against the ankle of the wearer, producing a slightly 45 and pleasing contour and appearance. The attachment is held to the ankle by a fastening-strap h , reaching around the ankle and connecting to a buckle i .

Having described my invention, what I 50 claim as new, and desire to secure by Letters Patent, is—

The design for an ankle attachment for overshoes, as herein shown and described.

In testimony whereof I affix my signature 55 in presence of two witnesses.

LAVINIA S. HODGSON.
